UNITED STATES PATENT OFFICE.

ROBERT H. POSTLETHWAITE, OF SAN FRANCISCO, CALIFORNIA, ASSIGNOR
TO THE RISDON IRON AND LOCOMOTIVE WORKS, OF SAME PLACE.

DRIVE MECHANISM FOR ROTARY GRIZZLIES OR SEPARATORS.

SPECIFICATION forming part of Letters Patent No. 625,274, dated May 16, 1899.

Application filed December 6, 1897. Serial No. 660,938. (No model.)

To all whom it may concern:

Be it known that I, ROBERT H. POSTLETHWAITE, a subject of the Queen of Great Britain, residing at San Francisco, in the county of San Francisco and State of California, have invented certain new and useful Improvements in Drive Mechanism for Rotary Grizzlies or Separators; and I do hereby declare that the following is a full, clear, and

exact description thereof.

The present invention relates to certain new and useful improvements in the drive mechanism for the rotating grizzly or separator used in connection with that class of dredgers known as "gold-dredgers," and it consists in the arrangement of parts and details of construction, as will hereinafter be fully set forth in the drawings and described and pointed out in the specification.

Owing to the continuous movement of the dredge boat, float, or platform upon which the rotary grizzly or separator and its drive mechanism are mounted, considerable trouble is experienced in so setting the drive mechanism to the inclined grizzly or separator as to permit of an even or regular motion being transmitted to the said grizzly or separator, due to the fact that the sudden jar of the boat, float, or platform, owing to the motion of the water

or strain of the machinery, serves to quickly work the drive mechanism out of line or apart, the lost motion thus created causing an uneven transmission of power to the said grizzly or separator.

The object of the present invention is to so support the shafting of the drive mechanism that the pinions thereof will at all times be held securely in mesh and be prevented from springing apart by reason of the jarring of the dredger itself.

In order to understand the invention, reference must be had to the accompanying sheet of drawings, forming a part of this application, wherein—

Figure 1 is a top plan view of the drive mechanism, said view showing a portion of the rotary grizzly or separator; and Fig. 2 is a side view in elevation of the mechanism illustrated by Fig. 1.

The rotary grizzly or separator A is arranged at an incline, and the upper end there-

of, which receives the gravel or material to be worked, is provided with cog-ring A', with which meshes the intermediate idler cog-wheel B, mounted upon the short shaft B'. This cog-wheel B receives its motion from the cog-pinion B², mounted upon the shaft B³, which shaft is arranged parallel with the shaft B', and said shaft is driven from the cross-shaft C by means of the intermeshing bevel-gears C' C², mounted upon the shaft B³ and cross-shaft C, respectively, Fig. 1. To one end of the cross-shaft C is secured the drive-wheel D', which is driven from any suitable machinery by means of a drive-belt. (Not shown.) The shaft B' works in bearing-box a of the bracket D², attached to the face of upright 1, and in bearing-box a', formed in the hub a², extending at a right angle to the bracket D³, attached to the face of upright 2, while the parallel shaft B³ works in bearing b, formed in the outer end of bracket D², and bearing b', formed in the outer end of bracket D³. It will thus be noticed that bearings a and b for the shafts B' and B³ are formed integral with the brackets D² and D³. Consequently neither shaft B' B³ nor intermediate idler cog-wheel B or cog-pinion B² can be moved or separated from each other without one of the brackets or bearing-boxes breaking.

The shaft B³ extends beyond the bearing b' and works through bearing d of the bracket E, bolted to the cross-timber 3. This bracket E is provided with an outwardly-extending curved arm E', which terminates in a bearing d', within which the cross-shaft C works, the opposite end of said shaft working in bearing d², attached to the top of timber 3. The bearings d and d' being integral with the bracket E, the bevel-gears C' C² will at all times be held in mesh. This manner of constructing the bearings—that is, two bearings for each bracket—and arranging the shafting forms a fixed connection between the parts and prevents the drive mechanism being moved apart or separated by jolting, jarring, or rough usage, which is an important feature in connection with machinery of this class, as it insures a steady uninterrupted movement being transmitted to the rotary grizzly or separator.

As the grizzly or separator when used in

connection with gold-dredgers is set at an incline, the trouble experienced in properly setting or running the drive mechanism is obviated where the bearings of the shafting are 5 formed integral with the brackets, for in such case the brackets are made in accordance with the inclination at which the grizzly or separator is set, and it is only necessary to bolt the brackets in place to secure the proper 10 angle or pitch of the shafting.

Having thus described my invention, what I claim as new, and desire to secure protection in by Letters Patent, is—

15 The combination with an inclined rotary grizzly or separator having a cog-ring attached thereto, of an intermediate gear meshing with said ring, a shaft for said gear, a second parallel shaft carrying a pinion meshing with

said intermediate gear, an inner bracket formed integrally with two bearings one for 20 each shaft, an outer bracket formed integrally with two bearings one for each shaft, a bevel-gear on said second shaft, a cross drive-shaft, a bevel-gear thereon meshing with said other bevel-gear, and a bracket formed integrally with two bearings arranged at an angle 25 to each other for said cross and parallel shafts, substantially as described.

In testimony whereof I affix my signature, in presence of two witnesses, this 30th day 30 of October, 1897.

ROBERT H. POSTLETHWAITE.
